UNITED STATES PATENT OFFICE.

CURT J. ROHLAND, OF WORCESTER, MASSACHUSETTS, AND JOHN H. WHEELOCK, OF FITZWILLIAM, NEW HAMPSHIRE, ASSIGNEES, BY MESNE ASSIGNMENTS, TO JOHN H. WHEELOCK, OF WORCESTER, MASSACHUSETTS.

SIGNAL AND ALARM SYSTEM.

Application filed February 5, 1915, Serial No. 6,349. Renewed April 30, 1921. Serial No. 465,927.

To all whom it may concern:

Be it known that we, CURT J. ROHLAND and JOHN H. WHEELOCK, citizens, respectively, of the German Empire and of the 5 United States, residing at Worcester, in the county of Worcester and State of Massachusetts, and Fitzwilliam, in the county of Cheshire and State of New Hampshire, respectively, have invented a new and useful 10 Signal and Alarm System, of which the following is a specification.

This invention relates to a signal and alarm system, particularly suitable for fire alarms, but capable of other uses. The 15 principal objects thereof are to provide a simple and compact arrangement so that all the mechanism required for giving several different alarms can be arranged within a small space; to provide means where- 20 by when a call box or thermo-switch or the like is operated at any of the different stations a visible or annunciator signal will be displayed automatically at the central station, a clock or other motor started there- 25 by and the displayed signal will be sounded at a number of different locations as desired; and to provide a construction in which at all times when a signal is displayed or a part of the system rendered active by 30 the operation of a call box or thermo-switch or the like a trouble signal, audible or visible, will be operated constantly so that the operator or any other person at the central station cannot possibly overlook the fact 35 that the system has been rendered active and has not been fully restored to its normal condition. Another feature of the invention is the arrangement of these parts in such a way that if after a signal is dis- 40 played, and while the same is being sounded, another branch of the system is rendered active, this will not interfere with the operation of the first signal and its alarm, but will simply cause a second signal to be dis- 45 played at the annunciator. The invention also involves improvements in the construction and arrangement, as well as the combination, of the parts.

In carrying out the principles set forth 50 herein an intermittent current conveyor is employed preferably of the nature of that represented in the Patents Nos. 1,178,431

and 2 patented April 4, 1916, and thermo- switches may also be employed which may be of any desired kind. 55

Reference is to be had to the accompanying drawings, in which—

Fig. 1 is a diagram of a system constructed in accordance with this invention showing the wiring; 60

Fig. 2 is a front elevation of the device, partly in section;

Fig. 3 is a sectional view on the line 3—3 of Fig. 2;

Fig. 4 is an end elevation of the drop 65 signal mechanism;

Fig. 5 is a plan of a portion of the same showing the trouble circuit controlling mechanism;

Fig. 6 is a front elevation of the clock 70 work controlling device, and

Fig. 7 is an end view showing in elevation the contacting magnet for the alarm and connected parts.

The drawings show the invention as used 75 with a closed circuit which is preferable, but the invention is not limited to the closed circuit arrangement.

Referring first to the diagrammatic view, Fig. 1, it will be seen that the mains A are 80 connected by a double-acting switch B with either one of two storage battery circuits G and C', one being the operating circuit and the other the emergency one, usually required. Connected directly with one of the 85 mains are a plurality of thermo-switches D, the details of which are not shown herein. They operate to open or close a circuit upon the melting of a fusible metal member. These can be arranged in series or multiple 90 or both, and the latter system is shown herein. A plurality of call boxes E are also shown which can be arranged in any desired way. They are shown each as being connected in series with a series of thermo-switches D. 95 Each of the branch circuits in which some of these thermo-switches and a call box are located is connected in series with an electro-magnet F, and these magnets are connected in multiple with each other and back 100 to the line. Each magnet when excited holds up a steel armature G which in turn holds a selector arm 46 up in inoperative position. Each of these armatures is provided with

a number on the face, and in Fig. 1 one of these is shown as dropped down so as to display the number 23 and thus indicate on which of the branch circuits the trouble 5 has occurred. It is to be noted that the main circuit to the clock work magnet Y is broken by the fall of any one of these armatures because it is normally completed by spring plunger contacts 55 between each 10 pair of which an insulated connection 56 is located. The circuit through the clock magnet Y also passes to the other side of the line through a "second alarm stop magnet N" in series.

15 In this figure annunciator or selector contacts are shown diagrammatically at H and numbered 1 to 8 inclusive. The branch circuits are periodically connected by the operation of the clock work with one side of 20 the line as will appear hereinafter. The other side of the line is connected through an electro-magnet P with the first one of the annunciator contacts H to be operated when the device is put into operation. This 25 magnet when excited closes the alarm circuit Q in which are alarm devices R.

Referring now more specifically to the selector mechanism shown in Figs. 2, 3 and 4, it will be seen that the branch circuit 30 numbered 1 in the diagram is constantly connected with the disc 17 also numbered 1, with a shaft 41 and with the magnet P. In stationary position around this shaft 41 are arranged a plurality of conducting rods 35 numbered 2^a to 8^a respectively each electrically connected with the corresponding branch circuit H. Each of these rods has a series of spring-pressed plungers 42 in alignment and arranged opposite each other 40 in pairs. On this shaft 41 are arranged a plurality of metallic circular discs 43, each located between the pairs of plungers 42 and capable of oscillating slightly about the shaft as a center. Each disc 43 is provided 45 with insulating surfaces 45 arranged in a circle but differently spaced so as to provide for preventing different ones of the plungers 42 contacting with their respective discs. Each disc has a radial arm 46 to the bottom of each of which is pivoted 50 one of the steel armatures G. Springs 47 individually connected with them tend to swing all of these arms down. These arms, however, are normally held up by the armatures and magnets. Each arm is provided 55 with a projection 48 and these projections are normally free to drop in slots 49 in a sliding locking plate 50 carried on the front of the frame 51 which supports these parts. 60 This sliding plate 50 is connected with the end of a lever T normally held by a magnet N in unlocking position. When the magnet N is deenergized and one of the armatures G dropped, this plate is moved by the spring 65 64 into the position shown in Fig. 2 so as

to hold up the ends of those arms that have not previously dropped. Then those plungers 42 are out of contact with the metal discs and no current can flow. The drop of one of the arms turns one of the discs so 70 as to bring some of its conducting surfaces between pairs of the plungers 42 and keeps others of these plungers insulated. In other words this sets the selector to control the giving of an alarm. In the position shown 75 in the drawings, the armature G having a signal #23 has dropped, the rest of the arms being held up by their armatures G in the position shown in Fig. 3, and also illustrated in dotted lines in Fig. 4. It is obvious that 80 the parts will remain in this condition as long as this branch circuit is broken anywhere, and consequently during this period if one of the other branch circuits is broken that armature G is also free to drop, and 85 does so. But this simply displays the second signal without operating the alarm because the corresponding arm is held up by the locking plate. The only way in which 90 an armature that has dropped or the arm thereof can be restored is by lifting it by hand, and it will not stay up unless that branch circuit has been restored.

The device as shown herein is arranged 95 to work on a closed circuit and when one of the thermo-switches D is rendered active by the melting of the fusible material which ordinarily makes the circuit through it or when any one of the call-boxes E is operated, that particular branch circuit through its 100 magnet F is interrupted and that armature G which that magnet normally holds up when excited is permitted to drop. The series circuit through contacts 55 and 56 is also interrupted by the fall of this armature. 105

The clock work I is provided with a magnet Y which is normally excited and holds its armature up to it, as shown in Fig. 6. This also holds the wheel 57, and consequently the clock work, from rotating in normal condition. Now when the circuit is broken by the fall of one of the arms 46 this magnet is de-energized and its armature left free. A spring 58 in Fig. 6 then forces back an insulating plunger 59 and 110 moves the armature back, swinging it on its pivot so as to allow the clock work to start. See dotted lines, Fig. 6.

Although the mechanism shown at the bottom of Figs. 2 and 3 and in Fig. 7 is illustrated and described in the first of the above mentioned patents, and therefore has not been described in detail herein, we shall describe the operation substantially in the language used in that application:—Upon the 125 turning of the shaft 14 by the clock work, one finger 23 will come into contact with the tooth 18 of the corresponding disc 17, and a little later the finger 29 will ride up on the corresponding tooth 20. No current 130

will flow however until the circuit is closed at the terminals 33 and 34 by the action of the finger 29. The current will be established from the line through contacts 33-34, 5 arms 32, shunt 40, brackets 15, shaft 14, one of the discs 17 the finger 23 that has come into contact with its tooth 18, selector or annunciator contacts 42, magnet P and the line A. It is to be observed that the finger 10 29 makes its contact while no current is flowing and the same is true of the several fingers 23. Consequently, no arc is made at these fingers upon the closing of the circuit and the usual difficulties due to the arcing 15 at these points are entirely avoided. Moreover, the current is broken at the terminals 33 and 34 while a finger 23 is still in contact with its tooth so that the arcing there is entirely avoided. Arcing at this time 20 between the finger 29 and tooth 20 is prevented by the shunt 40. This completes the circuit through the magnet P and draws the armature thereof up to the magnet and closes the circuit Q so as to give the first stroke 25 of the alarm.

The number #23 is the one displayed, and consequently the disc 43, having its contacts arranged to give that signal, is in operative position. As the tooth on the disc #2 30 next comes into position to make contact with its finger 23, a branch circuit will be completed through two plungers 42 in the manner that has been described. This connects that line with a conductor rod #2^a 35 which is also in communication with the line through magnets P. Thus a second stroke is given.

Now when the disc #3 comes into position in regular order to contact with its finger 23 40 no stroke will be given because that pair of plungers 42 are insulated from the disc 43 by one of the insulating surfaces 45. Thus a pause is caused at this point. Then the next three numbers 4, 5 and 6 will be 45 sounded in the same way as #2 and the signal 23 is thus completed during one complete rotation of the shaft 14. If the parts are so arranged that the shaft 14 rotates a plurality of times for each operation of one 50 of the arms 46 the sounding of the alarm 23 will be repeated accordingly.

Fig. 1 shows a trouble circuit K operated by the magnet N, which we call a second alarm stop magnet. When everything is all 55 right on the system and no signal is displayed the current flows through this magnet and attracts the end of the lever T in opposition to a spring S, and this causes a contact at X to be broken. But when the 60 circuit is broken at one of the contacts 56 through the operation of one of the armatures G the magnet N is immediately rendered dead and the spring S forces the lever T back to the position shown, which 65 closed the contact at X. This completes the

circuit through the trouble battery L and the trouble signal M and energizes the latter so that an audible or visible signal may be given as arranged for. In this case a gong 70 is shown at M. This trouble signal will continue to operate until everything is restored to normal condition.

There is another way in which this trouble signal can be given. The automatic movement of the armature of the magnet Y to 75 start the clock work also closes a contact V and completes a second circuit through the battery L, and signal M. The result of this is to cause this trouble signal to be given constantly at all times while the clock 80 work is operating, or not fully wound up, and also at all times when the current does not flow through the magnets N and Y. In either event this signal will be given constantly to show the operator the condition 85 of the mechanism.

From what has been said it will be obvious that when the system is in normal condition ready to operate, the armatures G are all held up by the magnets, but not by the locking plate, so that they can be released by the magnet and allowed to drop. These armatures hold up their respective arms 46 and therefore hold the discs 43 in inoperative condition, that is, with their insulating 90 surfaces 45 in contact with the plungers 42. The magnets N and Y are both energized so that the clock work is held from operating and the trouble circuit prevented from operating. The breakage of one of the branch 100 circuits in which the call boxes E and thermo-switches D are located immediately releases and displays a signal G. This has several immediate consequences. In the first place it lets down that arm 46 and 105 swings the corresponding disc 43 into such position that the selected contacts are made and ready to transmit the current to the magnet P whenever the shaft 14 rotates around to the proper position. It also breaks the main circuit through the conducting contacts 56 and thus de-energizes the magnets Y and N. The former releases its armature and thus automatically releases and starts the clock work so that the shaft 110 14 rotates and the signal is given through the instrumentality of the selector and the electro-magnets P. The magnet N releases the armature T and the spring S is free to pull the locking plate 50 over into position to hold up all the other arms 46. Furthermore, the de-energizing of the magnets Y and N, or either of them, starts the trouble circuit into operation and this signal, whether visible or audible or both, is 120 operated constantly until the line is entirely restored to normal condition. This trouble signal will keep operating until the thermo-switches D and call boxes E are all restored to normal condition and until all armatures 130

that may have dropped are moved upwardly by hand so as to come under the influence of their respective magnets and held up, thus also restoring the respective arms and discs. Furthermore, if the clock is left unwound the detent thereof cannot enter the notch in the wheel 57 and consequently the contact V cannot be opened by the mechanism. Therefore, the clock has to be wound up by turning the wheel 57 around to the position shown in Fig. 6 before the trouble signal will stop operating.

It is to be understood also that, after one armature G, as for example #23 has dropped as shown in Fig. 1 and the mechanism is in full operation, if some one turns in a call from another line, or it is done automatically by the melting of a fusible switch plug, that armature G will also swing down on its pivot and be displayed at the central station. But as the locking plate 50 has previously moved to the left the arm 46 connected with this second armature is locked and cannot drop. Consequently the operator is warned that another line is in trouble, but no alarm is given for this second line. The reason for this is that it frequently happens in case of a fire that some person will turn in an alarm from some near by station which does not indicate a second fire. The operator at the central station in this case can have an opportunity to find out whether there is a second fire, and if there is not, no further alarm is given and nothing need be done by the operator except to restore the two armatures instead of one, after the alarm for the first one has been given. However, if there is a second fire the operator can give that alarm by first restoring the first armature to proper position and holding it up, then operating the plate 50 by hand so as to allow the second arm to drop down and then releasing the plate so as to allow it to lock the first arm up with the others. Then the clock work is simply wound up and allowed to start and the second signal will be given.

Although we have illustrated and described only a single embodiment of the invention and shown it as applied only to a closed circuit installation, we are aware of the fact that many modifications can be made therein by any person skilled in the art without departing from the scope of the invention as expressed in the claims.

Therefore, we do not wish to be limited to all the details herein shown and described, but what we do claim is:—

1. In an electric alarm system, the combination with a main circuit and a branch circuit, of an electro-magnet in the branch circuit, an armature for the magnet, contact members connected with said main circuit beyond the branch circuit arranged and adapted to be connected when said armature

is attracted by the magnet so as to complete the main circuit, whereby when the armature is released the main circuit will be broken beyond the branch circuit, an alarm signal, a selecting device in series with the main circuit and in multiple with the branch circuit controlled by the release of said armature, and means whereby said selecting device will control the operation of said alarm signal and cause it to be operated to give a selected signal.

2. In an alarm system, the combination with a main circuit, having a plurality of branches in multiple, an electro-magnet in each branch, and an armature adapted to be held in a certain position by each magnet when energized and to move to another position when the magnet is de-energized and provided with means for displaying a signal when in one position, of a selector having an arm for each armature movable therewith, and mechanically connected with the selector, contact members arranged and adapted to be engaged by each arm when its armature is in one position for completing the main circuit through the arm, whereby when any arm is in one position, the main circuit will be broken, and an alarm device, said selector being connected with the main circuit and comprising means for controlling the operation of said alarm device, and causing it to be operated a predetermined number of times, with or without pauses, so as to give a signal representing a number, whenever said arm is moved to one position.

3. In an electric alarm system, the combination with a circuit having a plurality of branches in parallel, a plurality of electro-magnets each connected with one of said branches and in parallel with each other, an armature for each electro-magnet arranged to be held up when the magnets are energized and adapted to be displayed when released by the deenergizing of the magnet, said circuit having contacts arranged in series, means connected with each armature for completing the circuit through said contacts when all of said armatures are held up and whereby when one of them is displayed the circuit will be broken at that point, an alarm signal, and a selector connected with, and adapted to be set by, said armatures, said selector having means whereby the operation of said alarm signal is controlled by it.

4. In an alarm system, the combination of a selecting device comprising a plurality of series of contacts, a plurality of conducting members each in a position to be engaged by one series of contacts, means for normally holding said conducting members in a position in which the contacts will be out of contact therewith, and in position in which when turned slightly, a circuit will be made through the contact members at cer-

tain points, a circuit having branches provided with means for controlling the respective holding means, means in each of said branches for interrupting that branch and releasing the contact member connected therewith, an alarm signal, and means controlled by said contacting members for operating said alarm signal.

5. In an alarm system, the combination of 10 a selecting device comprising a plurality of series of contacts, a plurality of discs, each disc in position to be engaged by one series of said contacts, said disc being mainly of conducting material but having insulating 15 surfaces thereon, means for normally holding each disc in a position in which the contacts for engaging it will be in contact with said insulating surfaces thereof, the insulating surfaces of each disc being in such position 20 that when the disc is turned slightly a circuit will be made through the disc at certain points, a circuit having branches provided with means for controlling the respective disc holding means, means in each of 25 said branches for interrupting that branch and releasing the disc connected therewith, an alarm signal, and means controlled by said discs for operating said alarm signal.

6. In an automatic alarm system, the combination of a selecting device comprising a 30 plurality of contacts arranged in a circle, a plurality of discs, each disc arranged in position to be engaged by one circle of said contacts, said discs having insulating and conducting surfaces thereon, an electro-magnet for each of said discs, an armature adapted to be attracted and held up by each of said electro-magnets when energized, means connecting each armature with one of said discs 35 for holding it in position when the respective magnet is energized in which the contacts engaging it will be in contact with insulating portions of its surface, the conducting surfaces of each disc being in such 40 position that when the respective magnet is deenergized and the armature released, it will cause the disc to be turned to a position in which a circuit will be made through the disc at certain points, a circuit having 45 branches each of which connects with one of said magnets and having means in each of said branches for interrupting that branch and deenergizing the magnet connected therewith, an alarm signal, a motor, and 50 means controlled by said discs for operating said alarm signal.

7. In an automatic alarm system, the combination of a selecting device comprising a 55 plurality of conductors, each conductor having a plurality of contacts connected therewith, a plurality of discs, each disc arranged in position to be engaged by one series of said contacts, said discs having insulating and conducting surfaces thereon, means connected with each of said discs for normally

holding it in a position in which all of the conductors engaging it will be in contact with insulating portions of its surface, the conducting surfaces of each disc being in such position that when the disc is turned 70 electrical connections will be made through the disc at certain points, means for releasing said holding means and causing the disc to turn to make said electrical connections, means whereby one of the discs can be 75 turned to permit the passage of currents through the disc, an intermittent current conveyor having separate current conveying elements each connected with one of said contacts, and an alarm device constructed 80 to be operated in accordance with the connections made by the discs and contacts.

8. In an automatic alarm system, the combination of a selecting device comprising a plurality of parallel rods, each rod having a 85 plurality of contacts connected therewith, said contacts being arranged in a plurality of circles, in different planes, a plurality of discs, each disc arranged in position to be engaged by one circle of said contacts, said discs being mainly of conducting material but having insulating surfaces thereon, means for holding each disc in a position in which all of the contacts engaging it will be in contact with insulating portions of its 90 surface, the uninsulated surfaces of each disc being in such position that when the disc is turned, electrical connections will be made through the disc at certain points, a circuit having branches, means controlled by 95 each branch for operating the respective holding means, means in each of said branches for interrupting that branch whereby one of the discs will be turned to permit the passage of a current through the 100 disc and along certain of said rods, a plurality of branch circuits each connected with one of said rods, an intermittent current conveyor having separate current conveyor elements each connected with one of said last 110 named branch circuits, and an alarm device constructed to be operated in accordance with the connections made by the discs in said selecting device.

9. A selector for an alarm system comprising a plurality of parallel rods, each rod having a plurality of contacts connected therewith, said contacts being arranged in a plurality of circles in different planes, a plurality of discs, each disc arranged in position to be engaged by one circle of said contacts, said discs being mainly of conducting material but having insulating surfaces thereon, means for holding each disc in a position in which all of the contacts 115 engaging it will be in contact with insulating portions of its surface, the uninsulated surfaces of each disc being in such position that when the disc is turned, electrical connections will be made through the disc at 120

125 130

certain points, means for operating the respective holding means, a plurality of branch circuits each connected with one of said rods, and an alarm device constructed to be operated in accordance with the connections made by the discs in said selecting device.

10. A selector for an alarm system comprising a plurality of conductors, each conductor having a plurality of contacts connected therewith, a plurality of discs, each disc arranged in position to be engaged by one series of said contacts, said discs having insulating and conducting surfaces thereon, means connected with each of said discs for normally holding it in a position in which all of the conductors engaging it will be in contact with insulating portions of its surface, the conducting surfaces of each disc being in such position that when the disc is turned electrical connections will be made through the disc at certain points means for releasing said holding means and causing the disc to turn to make said electrical connections, and whereby one of the discs can be turned to permit the passage of currents through the disc.

11. A selector for an alarm system comprising a series of oscillatable discs having conducting and insulating regions, differently arranged on the respective discs, a plurality of series of contacts, each adapted to engage the conducting regions of one of the discs when the disc is turned to operative position, an arm connected with each disc for operating it, each arm having a conductor thereon insulated from the arm, a contact point mounted in position to engage each conductor and make electrical contact therewith, when the arms are in inoperative position, a circuit connected with said contact points, and means controlled by said circuit for controlling the passage of currents to said contacts.

45. 12. A selector for an alarm system comprising a series of independently oscillatable discs having conducting and insulating regions differently arranged on the respective discs, a plurality of series of contacts each adapted to engage the conducting regions of one of the discs when the disc is turned to operative position, and means for controlling the passage of currents to said contacts.

55. 13. In an alarm system, the combination with a signal movable to two positions, means for normally holding said signal in one of said positions and for releasing it to permit it to move to its other position when said means is rendered inoperative, a selector, means operated by the movement of said signal from one position to the other for setting the selector to control its operation, means controlled by the selector for giving a selected alarm, and an auto-

matic lock for preventing the resetting of the selector while the alarm is being given.

14. In an alarm system, the combination with a movable visible signal, means for normally holding said signal in concealed position, said signal being constructed and arranged to move and be displayed when said means is rendered inoperative, a selector, motor means for operating said selector, means controlled by the visible signal for starting the motor means when said signal is displayed, means controlled by the selector for giving a selected alarm, and automatic means for preventing the setting of the selector to give a different signal while the first named means is inoperative.

15. In an alarm system, the combination with a main circuit, having a plurality of branches, an electro-magnet in each branch, and an armature adapted to be held in a certain position by each magnet when energized and to move to another position when the magnet is de-energized, and provided with means for displaying a signal when in one position, of a selector having an arm for each armature, movable therewith, contact members arranged and adapted to be engaged by each arm when its armature is in one position for completing the main circuit through the arm, whereby when any arm is in one position the main circuit will be broken, an alarm device, said selector being connected with the main circuit and comprising means for controlling the operation of said alarm device, and causing it to be operated a predetermined number of times to give a signal representing a number, whenever said arm is moved to the position for breaking the main circuit, and means operative upon the motion of any arm to that position for preventing the other arms from moving to corresponding positions.

16. In a device of the class described, the combination with a selector having a plurality of arms, and selected signals on said arms but movable independently thereof, said arms being movable to operative and inoperative positions, of a locking device, and means whereby when an arm moves to operative position the other arms will be automatically locked in their initial inoperative positions.

17. In a device of the class described, the combination with a selector having a plurality of arms movable into two positions, in one of which they are operative and in the other of which they are inoperative, and means adapted to be set into operation by each of said arms when moved to operative position for giving a selected signal, of a locking plate having means for engaging each of said arms while in inoperative position and holding them there, means for normally holding said locking plate in inop-

erative position, and means whereby the locking plate will be released and allowed to move to operative position whenever one of said arms has moved into operative position.

18. In a device of the class described, the combination of a plurality of arms, means for normally holding said arms in inoperative position, said arms being arranged and adapted to move into operative position when released by said means, means controlled by each of said arms when moved to operative position for giving a selected signal, a locking plate for said arms arranged in position to lock the arms in their inoperative positions, means for normally moving said plate into its locking position, an electro-magnet connected with said locking plate and adapted to move it into unlocking position whenever said electro-magnet is energized, and means whereby when one of said arms moves into operative position while the magnet is energized, said magnet will be automatically disconnected from its source of power.

19. In a device of the character described, the combination of a plurality of oscillatable selector arms, an armature pivotally connected with the end of each arm, each armature having a character on its lower or front face, a series of electro magnets each in position for normally holding one of said armatures and its arm in a certain position, whereby if the magnet is de-energized the armature will be free to swing away from the magnet to display said character and the arm will be free to move with the armature, a sliding locking plate an electro magnet normally holding said locking plate in a position in which all of said arms are free to drop.

20. In a device of the character described, the combination of a plurality of selector arms, an armature connected with each arm, each armature having a character on its face, a series of electro magnets each in position for normally holding one of said armatures and its arm in a certain position, whereby if the magnet is de-energized the armature will be free to move away from the magnet to display said character, and the arm will be free to move with the armature, a locking plate, an electro-magnet normally holding said locking plate in a position in which all of said arms are free to move, a circuit connected with said last named magnet and having contacts one of which is adapted to be broken by the movement of any one of said arms, means whereby when said circuit is interrupted and the last named magnet de-energized, said locking plate will be moved into a position to prevent all of the other arms from moving,

whereby the rest of the armatures will be left free to move down.

65

21. A selector for an alarm system comprising a member having conducting and insulating regions, a plurality of series of contacts each adapted to engage one of said conducting regions in certain positions thereof, an arm connected with each conducting region for operating it, each arm having a conductor thereon insulated therefrom, a contact point mounted in position to engage each conductor and make electrical contact therewith when the arms are in inoperative position, a circuit connected with said contact points, and means controlled by said circuit for controlling the passage of currents to said contacts.

80

22. In a device of the character described, the combination with a circuit and an electro magnet therein, of a series of movable selector members each having means for completing contacts in said circuit, a clock work connected with the selector mechanism for operating the same, a detent for preventing the operation of the clock work, an armature connected with said detent, an alarm circuit having a pair of contact points therein, means connected with said detent for holding said contact points apart when the armature is attracted by the magnet, and means for moving said parts together when the armature is released.

95

23. In a device of the character described, the combination with a circuit, and an electro magnet therein, of a series of movable selector members, each having means for completing contacts in said circuit when said selector means is in operative position and for interrupting said circuit when any one of them is moved to inoperative position, of a clock work connected with the selector mechanism for operating the same, a detent for preventing the operation of the clock work, an armature connected with said detent and adapted to be normally held by the magnet in a position to keep the detent in condition to prevent operation of the clock work, an alarm circuit having a pair of contact points therein, means connected with said detent for holding said points apart when said armature is attracted by the magnet, and means for moving said parts together when the armature is released.

100

In testimony whereof we have hereunto set our hands, in the presence of two subscribing witnesses.

CURT J. ROHLAND.
JOHN H. WHEELOCK.
